UNITED STATES PATENT OFFICE.

CHARLES W. MCGONIGLE, OF ALGONA, WASHINGTON; ASSIGNOR TO GLOBE TELEPHONE COMPANY, OF SEATTLE, WASHINGTON, A CORPORATION OF WASHINGTON.

TELEPHONE SYSTEM.

1,076,990.

Specification of Letters Patent.

Patented Oct. 28, 1913.

Application filed July 15, 1912. Serial No. 709,459.

To all whom it may concern:

Be it known that I, CHARLES W. MCGONIGLE, a citizen of the United States, residing at Algona, in the county of King and State 5 of Washington, have invented certain new and useful Improvements in Telephone Systems, of which the following is a specification.

This invention relates to telephone apparatus and particularly where the same is operated on a wire or wires of a telephone system and where the various currents passing thereover have a disturbing influence upon the voice sounds of the telephone.

10 The object of the present invention is, first, to afford a telephone current of relatively low potential by preventing the currents of high resistance receiving instruments being cut into the line by including 15 in the line a high frequency transformer primary coil of small ohmic resistancy and utilizing the secondary coil of the transformer with a telephone receiver of high resistance; second, to afford means whereby 20 the induction current of higher frequency than voice sounds will pass through a condenser provided in a shunt across the primary of the high frequency transformer, as such resistance offers less resistance than a 25 coil to high frequencies; third, to provide a path for frequencies lower than that generated by voice sounds and with less resistance to such currents than the relatively high resistance offered by a telephone receiver 30 and condenser; fourth, to provide means for sending a preliminary signal, as the ringing of a bell; and fifth, to provide means for cutting into the main line of the secondary terminals of a telephone induction-coil when 35 40 speaking and cutting the same out when receiving a telephone message.

With these and other ends in view, the invention consists in the novel arrangement and adaptation of parts, as will be herein- 45 after described and claimed.

The accompanying drawing is a diagram illustrating an embodiment of my invention.

The reference numerals 1—1 designate an 50 electric transmission line, or main line, having therein the primary coil 3 of a high frequency air core transformer. 4 represents a condenser provided in a shunt extending between the terminals of said coil. 55 5 is the secondary coil of said transformer.

whose terminals are connected to wires 6 and 7 and constitute a normally incomplete circuit with a gap between the terminals 6' and 7' thereof. Included in the circuit is a telephone receiver R and a condenser S. An 60 impedance coil 9 having a movable iron core 9' is shunted between the wires 6 and 7 as indicated in the view. 6² and 7² are branches to the respective wires of said circuit and are provided with terminals 6³ and 7³ which 65 are disposed to be engaged by the members 10 and 11 of a bipolar switch which are connected to the helix of the magnet 12 of a high resistance telephone receiver. The dia- 70 phragm 12' of this receiver is operatively 75 connected with a lever 13 having its short arm pivoted to an element 14, while its long arm carries a finger 13' to cooperate with a quantity of mercury provided in a cup 15. The latter is supported by an adjustable 80 screw 16 extending through a screw threaded hole in a fixed element 17. A battery 18 and a signal bell 19, or an equivalent, are provided in a local, or relay, circuit which includes wires 20, and whereof the finger 13' 85 and said mercury serve as the terminals. The above described parts constitute the receiving portion of a telephone system. The sending portion thereof consists of a telephone transmitter T and a battery 21 upon 90 the circuit of an induction coil 22 of a trans- 95 former, the other coil of which is shunted with said main line to bridge a gap therein when the closure 23 for the same is open.

In operation, the main line closure 23 is 90 opened when the transmitter T is to be em- 95 ployed and is in its normally closed posi- 100 tion at all other times. When the message is to be delivered to the receiver, an induced current passes from coil 5 through the cir- 105 110 115 120 125 130 135 140 145 150 155 160 165 170 175 180 185 190 195 200 205 210 215 intended for use with a single wire ground return circuit, but it may obviously be used on a complete metallic circuit.

Among the advantages of the invention, 5 are that remote instruments will receive as distinct and loud communications as those closer to the sending instrument, and it may be used for the transmission of a number of concurrent conversations over a single main 10 line by the provision of widely different induction coils for the various transmitters and the use of high frequency alternating current in the primary circuit of the transmitters and by carefully adjusting the respective condensers and impedance coils. 15

What I claim, is:—

1. In a telephone system, the combination with the main line embracing the primary coil of a transformer, a normally incomplete 20 circuit embracing the secondary coil of said transformer, and a telephone receiver and a condenser on said circuit, of a normally incomplete relay circuit, a signal instrument in the latter, a shunt circuit embracing the 25 magnet of a high resistance telephone receiver, a diaphragm for this receiver, a closure for the opening in said relay circuit, operatively connected with said diaphragm,

a switch adapted to be selectively employed for closing said incomplete circuit or for 30 conductively connecting said relay circuit with the first named circuit.

2. In a telephone system, the combination with the main line embracing the primary coil of a transformer, a shunted condenser between the terminals of said primary coil, a normally incomplete circuit embracing the secondary coil of said transformer, and a telephone receiver and a condenser on said circuit, of a normally incomplete 35 relay circuit, a signal instrument in the latter, a shunt circuit embracing the magnet of a high resistance telephone receiver, a diaphragm for this receiver, a closure for the opening in said relay circuit, 40 operatively connected with said diaphragm, a switch adapted to be selectively employed for closing said incomplete circuit or for conductively connecting said relay circuit with the first named circuit. 45

Signed at Seattle, Washington, this 6th day of July 1912.

CHARLES W. McGONIGLE.
